Primary Examiner — Martie K Holtje*(74) Attorney, Agent, or Firm* — Adams & Wilks(57) **CLAIM**

The ornamental design for a metronome, as shown and described.

DESCRIPTION

FIG. 1 is a front, right bottom perspective view of a metronome showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The structural elements depicted by broken lines in FIG. 3 have been shown for the purpose of illustrating portions of the metronome that form no part of the claimed design.
